HEADBOARD FOR A BED

Norman N. Hekler, High Point, N.C., assignor to Worth Furniture, a division of Gravely Furniture Co., Inc., Martinsville, Va., a corporation of Virginia

Original design application Nov. 27, 1962, Ser. No. 72,612. Divided and this application Mar. 26, 1963, Ser. No. 74,133

Term of patent 3½ years

(Cl. D5—2)

FIG. 1

FIG. 1 is a perspective view of a headboard for a bed, showing my new design;

FIG. 2 is a top plan view thereof, on an enlarged scale; and

FIG. 3 is a front elevational view thereof.

The back of the headboard is conventionally plain.

This application is a division of my application Serial No. D. 72,612, filed November 27, 1962, and now abandoned.

I claim:

The ornamental design for a headboard for a bed, as shown and described.
